SAFETY APPARATUS FOR OIL BURNERS

William C. Groff, St. Louis, Mo.

Application February 27, 1930. Serial No. 431,753

4 Claims. (CL. 175—115)

This invention relates to oil burners and similar devices of the type that employ a spark plug, electrodes or other electric spark-producing means for igniting oil, gas or other combustible mixture used to operate the burner.

Many serious accidents have occurred in burners of the general type mentioned, due to the sparking means failing to create a spark at the time the electric motor of the fuel supply means or atomizing means is set in operation, and thereafter producing a spark after the combustion chamber with which the burner is used has become loaded or overcharged with a gaseous fuel mixture. In various makes or kinds of electrically-ignited oil burners that are now on the market such a delayed spark is liable to be produced, in the event of a flame failure or ignition failure, when the safety device of the burner comes into operation, and opens or interrupts the circuit that supplies electrical energy to the transformer of the ignition system and to the electric motor that drives the fuel pump or air blower. The reason for this is that the electrical energy which flows into the transformer when the spark plug, electrodes or other spark-producing means fails to function properly after the fuel pump or air blower has been set in operation, causes considerable electrical energy to be stored up in the transformer, and when the supply of electrical energy to the transformer is subsequently interrupted by the functioning of the safety device of the burner, such stored electrical energy will create a faint spark across the points of the spark plug or electrodes, and thus produce what I have previously referred to as a "delayed" spark that will explode the gaseous mixture that has accumulated in the combustion chamber.

The main object of my invention is to overcome or eliminate the possibility of accidents of the kind referred to. To this end I propose to equip an electrically ignited fuel burner with a means that will prevent a spark being created by the spark plug, electrodes or similar means of the burner at a time when the combustion chamber with which the burner is used is filled, loaded or overcharged with a gaseous mixture that has accumulated in said chamber, due to a flame failure, ignition failure or power failure.

I have herein illustrated my invention embodied in an electrically-ignited oil burner of conventional design, provided with a spark-producing means composed of electrodes to which a high tension electric current is supplied from a transformer, but I wish it to be understood that

my invention is not limited to use with any particular make or kind of electrically-ignited fuel burner, and further, that various means may be employed to accomplish the highly desirable results attained by my invention, such, for example, as a short-circuiting device, a shunt, a condenser, a resistance, a lamp or tube or a grid-leak. In an oil burner of the type herein illustrated an accidental spark that might cause an explosion, can be positively prevented by the use of a device or means that will short-circuit the high tension leads on the transformer or the conductors through which the high tension current is carried from the transformer to the points of the sparking means, or by the use of a device or means that will ground, shunt or divert high tension current discharged from the transformer. The device or means that is used for either of the purposes above referred to may be arranged externally of the transformer or some other part of the ignition system, or it may be built into the transformer or some other part of the system, so as to form in effect an integral portion of said part. If a short circuit device is employed, said device may be designed so that it will cause the high tension current to be short-circuited either by opening the circuit, or by closing the circuit, and any suitable or preferred means may be used to actuate said device or cause it to operate.

In view of the multitude of devices or means that may be used to prevent the sparking means of the burner from producing or creating a spark at a time when such a spark might cause an explosion in the combustion chamber of the apparatus with which the burner is used, I will not attempt to describe or enumerate all of the devices or means that may be used for this purpose. Suffice it to say that my invention, broadly stated, consists of an electrically-ignited fuel burner that comprises a spark-producing or creating means, a transformer or similar apparatus for supplying high tension electric current to said sparking means, a safety device of the kind now generally used in oil burners, or any other suitable type or kind, constructed or arranged so as to automatically cut off the supply of electric current to the transformer in the event of a flame failure, ignition failure or power failure, and a means that will operate automatically in advance of or prior to the interruption or cutting off of the energizing circuit of the transformer, for positively preventing high tension current from discharging from or passing from the transformer to the sparking means.

Figure 1 is a diagrammatic view of an electrically-ignited oil burner embodying my invention.

Figure 2 is an enlarged detail, showing the 5 transformer, the time switch, the short-circuiting apparatus and the electrodes; and

Figure 3 is a side elevational view of the short-circuiting apparatus, showing how the armature of same moves automatically into a position to 10 render the short-circuiting bar operative, whenever the coil of said apparatus becomes de-magnetized or de-energized due to functioning of the time switch.

In the accompanying drawings, A designates 15 the electrodes or other spark-producing or creating means of an electrically-ignited oil burner, B designates a transformer that supplies high tension electric current to said electrodes or sparking means, 1 designates the supply lines by which 20 low tension electric current is supplied to the transformer, C designates an electric motor that is used to drive a fuel pump or air blower or to drive both of said elements, so as to deliver atomized fuel to the combustion chamber of the heating apparatus with which the burner is used, and 25 D designates as an entirety a safety device, such as is now commonly used in oil burners, so as to automatically cut off the supply of electrical energy to the transformer B and motor C in the 30 event of a flame failure or ignition failure. For example, if the flame fails when the burner is in operation, the device D will act in such a way as to stop the motor C and prevent current from flowing into the transformer B. Likewise, if the 35 sparking means A fails to produce a spark when the control switch or thermostat E is actuated to set the motor C in operation, the safety device D will act in a few seconds or in a few minutes to stop the motor and cut off the supply of current to the transformer. During the period the 40 motor C remains in operation prior to the functioning of the safety device D, a considerable quantity of combustible mixture accumulates in the combustion chamber of the apparatus with 45 which the burner is used. A considerable quantity of electrical energy is also stored up in the transformer B during this period, due, of course, to the fact that there is no electrical discharge from the electrodes A. When the energizing circuit 50 of the transformer is opened or interrupted by functioning of the said safety device, the electrical energy which has been stored up in the transformer is apt to be discharged from the transformer and create a faint spark across the 55 points of the electrodes, and if this occurs, the gaseous mixture in the combustion chamber will be ignited, often with very disastrous results.

In order to remedy or overcome the above described inherent defect of an oil burner equipped 60 with a transformer that supplies high tension electric current to spark-producing means, I propose to equip the burner with a means that will act in advance of or prior to the cutting off of the supply of current to the transformer, and operate in such a way as to positively prevent high tension current from being discharged from the transformer B, or passing from said transformer to the sparking means A. In the burner herein shown the means just referred to consists of a 65 short-circuiting apparatus F combined with a timing switch G in such a way that in the event of a flame failure, an ignition failure or a power failure, the timing switch G will cause the apparatus F to act and move a short-circuiting bar 2 into such a position that the leads 3 which con-

nect the sparking means A with the transformer B will be short-circuited. Various types or kinds of timing switches G may be used, so long as said timing switch is installed in the ignition circuit in such a manner and is of such construction that it will act or operate in advance of the safety device D. In the burner herein shown the timing switch G and the short-circuiting apparatus F are of such design (see description of operation) that when the burner is operating normally, or when the motor C is set in operation and the sparking means A functions properly to produce a spark, the short-circuiting bar 2 will be maintained in an inactive or inoperative position, wherein it does not interfere with the passage of the high tension current from the transformer B to the sparking means A. If, however, a flame failure, ignition failure or power failure occurs, the conjoint action of the timing switch G and short-circuiting apparatus F will render the short-circuiting bar 2 operative before the safety device D causes the supply of electric current to the transformer B to be interrupted. Hence, a discharge of high tension current from the transformer, resulting from an interruption of the 100 supply of electrical energy to the transformer, would have absolutely no effect on the sparking means A, because when such a discharge occurs, the sparking means A is positively cut off from the transformer. It will thus be seen that even 105 though the combustion chamber is filled with a combustible mixture, there is no danger of said mixture exploding.

The short-circuiting apparatus herein illustrated consists of a magnet provided with a coil 110 4 and with a pivoted armature 5 to which are attached arms 6 that carry the short-circuiting bar 2, which is adapted to co-operate with contacts 7 arranged in the leads 3 between the sparking means A and the transformer B. The timing switch G is connected with the coil 4 in such a way (see description of operation) that under normal operating conditions the coil 4 will be energized, thereby maintaining the armature 5 in its inactive or inoperative position, shown in Figure 3, and causing the short-circuiting bar 2 to be held spaced away from the contacts 7. When the coil 4 becomes de-energized, or de-magnetized by functioning of the timing switch G, when a flame failure, ignition failure, or power failure occurs, the armature 5 will swing outwardly into the position shown in full lines in Figure 3 and the short-circuiting bar 2 will move into engagement with the contacts 7, and thus create a dead short across the leads 3 before the safety device D acts to cut off the passage of current from the supply mains 1 to the transformer B.

Relay No. 1 controls switch 35 by mechanical means (not shown) to close the switch when the relay opens, and to release the switch for opening when the relay closes. Starting switch or contact 13 is mechanically connected with the bimetallic element 41, by means not shown, and is opened during motion of the bimetallic element to the left as result of application of heat by coil 40. Contact 13 is in the starting circuit of No. 1 relay and, therefore, in case of a shut-down and opening of relay No. 1, a restart or re-energization of No. 1 can only be had after element 41 has moved to or is near the position shown in the drawings.

Operation

The drawings show the position of the parts just after closure of the room thermostat on a "call for heat", with the bimetallic element 41

positioned to the right of the shoulder 42 to prevent opening of the switch 35, and with the stack thermostat or flame responsive device 50 open, relay No. 2 de-energized, contact 15 of the starting or energizing circuit of relay No. 1 closed, and contact 53 of the circuit for energizing the low tension side of the transformer closed, it being understood that these contacts will be opened on energization of relay No. 2, and that contacts 17 and 59 will be closed. The element R has moved to successively engage contacts W, B, and relay No. 1 is energized through the following circuit: one side of secondary 10 of the transformer, thermal safety switch 11, W, R, B, conductor 12, safety switch 13 (mechanically connected to element 41 to be opened by 41 as it moves to the left), conductor 14, starting contact 15 of relay No. 2, switch arm 16, conductor 18, coil 19 of the thermal safety switch, conductor 20, coil 9 of relay No. 1, conductor 21 to the opposite side of the transformer secondary 10. Holding contact 25 controlled by relay No. 1 is closed, as well as motor contact 26, also controlled by relay No. 1. Motor C is energized through the following circuit: 27, 28, motor contact 26, 29, one side of motor C, and from the other side by conductor 30 to line 31. At this time, the switch arm 35 of the timing switch is making with contact 36 (being so held by element 41 which is in "cold" position) and, therefore, coil 4 is energized through the following circuit: 27, 28, motor contact 26, 29, 36, 35, 37, coil 4, 38 to line 31. The armature 5 to which are attached the arms 6 which carry the short-circuiting bar 2 is now holding the bar 2 to prevent short-circuiting, it being understood that the armature is biased to automatically move the bar to short-circuiting position, on de-energization of coil 4. At this time the bimetallic element 41 of the timing switch is arranged at the right of the shoulder 42 so that the switch is held against contact 36 or in closed position. The bimetallic element 41 is now being heated and is moving toward the left. At the end of some predetermined period, 41 passes the shoulder 42 and switch arm 35 moves in the direction of the arrow to break contact 36. During motion of 41, contact 13 has been opened and inasmuch as this contact 13 is in the closing or starting circuit of relay No. 1, this relay cannot again be closed until 41 assumes its right-most, or nearly right-most, position. The switch 35 opens at the end of about one and one-half minutes and, as a result of this opening, coil 4 is de-energized and the short-circuiting bars move to short-circuiting position so that there can be no sparking across the electrodes of the igniter, although the low tension side of the transformer remains active. When the switch 35 opens, the current to the heating coil 40 is also interrupted and if it were not for the shoulder 42, the element 41 (now cooling) would move to the right to assume its original cold position. The element 41, therefore, remains at the right and switches 35 and 13 remain open. Under conditions later to be described, when relay No. 1 is de-energized, switch 35 is automatically raised to closed position so that the element 41 can assume the cold position, to itself hold the switch in closed position independently of the switch closing and holding means operated by relay No. 1.

Continuing the operation.—The opening of switch 35 has occurred because flame was not produced, and the sparking apparatus is now conditioned so that it cannot act. At the end of about a half a minute, after switch 41 has moved to open position, heating element 19 which was

energized on closure of the thermostat, causes the thermal safety switch 11 to open, and opens the holding circuit for coil 9 so that relay No. 1 is de-energized and contacts 25 and 26 are opened. Ordinarily the safety switch has means for locking it in open position, so that the apparatus cannot operate automatically until the switch is manually closed, which is not done until after inspection and repair of any inoperative elements of the system.

Also under this condition of no-flame production, the stack thermostat 50 remains open, the coil 51 of relay No. 2 is not energized, and the switch arms 16 and 52 remain in engagement with respective contacts 15 and 53. Transformer B is receiving current through the following circuit: 27, 54, 52, 53, 55, transformer B, 56 to line 31, but although the transformer is thus energized, there is a short circuit across lines 3 and no spark can pass. According to the circuit arrangement just described, the transformer B is always energized except during flame period. This is wasteful, and it is better to de-energize the transformer whenever the motor is de-energized. For this purpose, switch 52 can be connected with line 29, and connection 54 and contact 59 can be dispensed with. In any event, the spark or ignition means is always rendered inoperative when switch 35 opens. This is an important feature.

It will be noted that even if flame is produced, the switch 35 will open at the end of a predetermined period, because element 40 is being heated by a circuit which is closed by the motor contact 26. The opening of switch 35, therefore, results in de-energization of coil 40, and 41 begins to cool, but cannot move to its initial right-hand position because of shoulder 42 or its equivalent. Motion of the element 41 from the right-most to the left-most position opens switch 13 and breaks the starting or closing circuit of relay No. 1. After opening of switch 35, the shunt for lines 3, 3 is closed so that whatever the electric condition of the transformer B, no sparking at the electrodes can occur to cause explosion. In case flame is produced before safety switch 11 is opened (as the result of prolonged heating of the element 19) relay No. 1 remains energized, the motor remains energized, and flame responsive switch 50 closes and by this closure, relay No. 2 is energized through the following circuit: 27, 54, coil 51, 57, contact 50, 58 to 31 and as a result, arms 16, 52 controlled by relay No. 2 move to engage respective contacts 17, 59. The closure of contact 17 shunts out the heating coil 19, the holding circuit for the relay No. 1 then being as follows: 10, 11, W, R, 60, contact 25, 61, 18, 16, 17, 62, 9, 21 to 10. By closure of contacts 59, coil 4 is energized through the following circuit: 27, 54, 52, 59, 63, 37, coil 4, 38 to 31, and coil 40 is energized through the following circuit: 27, 54, 52, 59, 63, 37, 43, 40, 44, to 31. Thus energization of coils 4 and 40, and open circuit condition of lines 3—3 is maintained while flame is present.

Having thus described my invention, what I claim as new and desire to secure by Letters Patent is:

1. In an electrically ignited fuel burner, the combination of a sparking means, a transformer for supplying high tension current to said means, a short-circuiting device for preventing high tension current from passing from the transformer to said sparking means under certain conditions, a magnet comprising a coil and an armature that

150

actuates said device, and a timing switch in the ignition circuit for governing said magnet, adapted to cause said short-circuiting device to be rendered operative to prevent sparking in the event of a flame failure, ignition failure or power failure.

2. A transformer having the usual high tension and low tension circuits, a shunt for the high tension circuit, means for controlling the low tension circuit to open it, and means acting automatically before opening of the low tension circuit to close the shunt of the high tension circuit.

3. In an ignition system a sparking igniter, and a transformer, a circuit connecting the igniter with the high tension side of the transformer, means for short-circuiting the high tension circuit to prevent sparking, a timing switch having

a heating element for opening it, and circuits for controlling said heating element, and short-circuiting means by said timing switch.

4. In an ignition system a sparking igniter and a transformer, a circuit connecting the igniter with the high tension side of the transformer, means for short-circuiting said high tension circuit to prevent sparking, means for delivering fuel for ignition, a circuit for the low tension side of the transformer, means responsive to production of flame adapted to open the said low tension circuit when flame is produced, a timing switch having a heating element for opening it, and circuits for controlling said heating element, and short-circuiting means through said timing switch.
